UNITED STATES PATENT OFFICE.

WALTER F. KEENAN, JR., OF PELHAM, NEW YORK, ASSIGNOR TO FOSTER WHEELER CORPORATION, OF NEW YORK, N. Y., A CORPORATION OF NEW YORK.

RADIANT-HEAT SUPERHEATER FOR BOILERS OF THE LOCOMOTIVE TYPE.

Application filed May 19, 1924. Serial No. 714,309.

The general object of my present invention is to provide a boiler of the locomotive type with improved steam superheating provisions. More specific objects of the invention are to provide a boiler of the locomotive type with a superheater absorbing radiant heat from the combustion chamber of the boiler and giving a desirably high superheating effect although comparatively small in bulk and weight; and which is simple in construction and arrangement, and so disposed as to facilitate inspection, cleaning and repairs; and which will reduce the stresses and strains in the portion of the boiler structure, to-wit: the crown sheet, which is subjected to the most severe operating conditions in locomotive boilers as now constructed.

The various features of novelty which characterize my invention are pointed out with particularity in the claims annexed to and forming a part of this specification. For a better understanding of the invention, however, its advantages, and specific objects obtained with its use, reference should be had to the accompanying drawings and descriptive matter, in which I have illustrated and described a preferred embodiment of the invention.

30. Of the drawings:

Fig. 1 is a sectional elevation of a portion of a boiler of the locomotive type;

Fig. 2 is a section on the line 2—2 of Fig. 1;

35. Figs. 3 and 4 are partial sections, each taken similarly to Fig. 2, and each illustrating a different modification;

Fig. 5 is a view taken similarly to Fig. 1 illustrating a longitudinal arrangement of the superheater elements; and

Fig. 6 is a section on the line 6—6 of Fig. 5.

In the drawings, and referring first to Figs. 1 and 2, A represents the shell of a 45. boiler which is of the locomotive type, though the boiler actually shown in these figures was especially designed for use on a river steamboat. B represents the boiler fire box or combustion chamber, the roof of which is formed by the usual crown sheet C. Fire tubes or flues D are connected at their rear ends in the usual manner to the tube sheet B' forming the front wall of the combustion chamber B. The steam generated in the boiler passes through the connec-

tion A' into a steam drum or chamber E mounted above the boiler shell.

From the drum E the steam passes through the pipe E' to the superheater inlet header H. The latter is divided into an inlet compartment h and an outlet compartment h' by a transverse partition H'. The steam pipe E' opens to one end of the compartment h. From the compartment h the steam passes through a plurality of superheater elements F to the intermediate superheater header I, and then passes through the remainder of the superheater elements F to the outlet chamber h' in the header H, from which the superheated steam passes to the engine through piping (not shown) connected to the superheated steam outlet H'. The superheater elements F in the construction shown in Figs. 1 and 2 are each in the form of an arc-shaped flattened tube of cast 75 steel which extends transversely to the length of the boiler and is located just beneath the crown sheet C and is curved to correspond to the contour of the latter. Each element F has connected to it at each 80 end a transversely extending tube G, the tube G at one end of the element being connected into the corresponding compartment h or h' of the header H, while the tube G at the opposite end of the element is connected into the header I. The tubes G pass 85 loosely through stay tubes K connecting the boiler shell to the crown sheet C. To prevent chilling of the superheater elements F and tube connections G thereof, refractory material is interposed between the crown sheet and the upper sides of the superheater elements, and between the tubes G and the surrounding stay tubes. This refractory material L may well be a cement such as is used in the construction of baffle walls. In addition to preventing the transfer of heat from the superheater to the water space walls of the boiler, the refractory material prevents gas flow along the back of the 100 superheater. The headers H and I are secured by yokes J' to saddle blocks J riveted to the boiler shell. The elements F unite to provide a smooth heat absorbing under surface generally similar in contour to the under side of the crown sheet C and sufficiently close thereto to avoid material reduction in the gas space of the fire box.

With the apparatus described, it is possible to obtain a relatively high superheating 110

effect with a comparatively small amount of superheating surface, and with superheating means which are simple in construction, and durable, and which do not interfere with the operation of the boiler except as they do so advantageously by reducing the heat absorption by the crown sheet where the heat absorption is normally undesirably intense. The elements F may well be formed each of a single steel casting, as the length of the elements, their shape, and the manner in which they are supported permit of their contraction and expansion in response to changes in the temperatures to which they are heated, without causing objectionable deformation of the elements or without subjecting the elements or their tube connections to objectionable stresses, the tube connections being sufficiently flexible to accommodate the bodily elongation and contraction of the elements F relative to the boiler shell and also any warping or bending of the elements F resulting from the fact that in operation their under sides are hotter than are their upper sides. The tubes G may be secured to the elements F and to the headers I by expanding their ends into place as tubes are commonly expanded into headers and tube sheets, and when repairs or renewals are necessary, it is a comparatively simple matter to cut the tubes G out and then replace them by new ones.

To facilitate repairs and renewals the tubes G may be vertical as shown in Fig. 3, in which case when the two tubes G connected to each element F are detached from the headers H and L, the element may be lowered into and then withdrawn from the combustion chamber B.

A superheater constructed and arranged as shown is well adapted to withstand very high temperatures, and hence in some cases it will not be necessary to provide means for protecting the superheater against overheating during the periods in which no steam is drawn through the superheater. When it becomes necessary or desirable to flood the superheater with water, this may be accomplished by means of a pipe connection M' containing a circulating pump M as shown in Fig. 3, which forces water from the boiler shell into the compartment h' of the header H, and thence through the superheater elements F, header I, pipe E' and drum E back into the boiler shell. M' is a cut-off valve in the connection M'. By locating one of the superheater headers below the boiler water level as the header I is shown in Fig. 4, the superheater may be flooded by connecting the lowered superheater header to the boiler water space as by means of the valved pipe connection O shown in Fig. 4. In this arrangement the bodily elongation and contraction of the elements F must be accommodated mainly or

entirely by the flexure of the tube G connected to the header H. Instead of arranging the superheater elements transversely of the longitudinal axis of the boiler they may be arranged parallel thereto as in Figs. 4 and 5. The superheater elements FA shown in Figs. 4 and 5 are straight, while the header elements HA and IA are curved and transverse to the boiler axis. The headers HA and IA are connected to the elements FA and to the boiler steam pipe E' in the same manner as the headers H and I are connected to the elements F and steam pipe E in the construction first described.

While in accordance with the provisions of the statutes, I have illustrated and described the best forms of embodiment of my invention now known to me, it will be apparent to those skilled in the art that changes may be made in the form of the apparatus disclosed without departing from the spirit of my invention as set forth in the appended claims, and that in some cases certain features of my invention may be used to advantage without a corresponding use of other features.

Having now described my invention, what I claim as new and desire to secure by Letters Patent, is:

1. In a boiler comprising an internal combustion chamber with a crown sheet roof and flues leading away from the combustion chamber, the improvement which consists in a radiant heat superheater comprising a plurality of conduit elements arranged side by side in the combustion chamber immediately beneath the crown sheet.

2. In a boiler comprising an internal combustion chamber with a crown sheet roof and flues leading away from the combustion chamber, the improvement which consists in a radiant heat superheater comprising a plurality of conduit elements arranged side by side in the combustion chamber immediately beneath the crown sheet, and heat insulating material interposed between the superheater elements and the crown sheet.

3. In a boiler comprising an internal combustion chamber and a crown sheet forming the roof thereof and provided with fire tubes leading away from the combustion chamber, the improvement which consists in a radiant heat superheater composed of elements located beneath the crown sheet, tubes connected to the elements and extending to the exterior of the boiler, and stay tubes connecting the combustion chamber and boiler shell walls through which said tubes extend.

4. In a locomotive boiler comprising an internal combustion chamber and a crown sheet forming the roof thereof and provided with fire tubes leading to the front end of the boiler from the combustion chamber, the improvement which consists in a radiant heat superheater composed of elements ex-

tending transversely to the length of the boiler beneath the crown sheet, tube connections to the ends of the elements extending to the exterior of the boiler, and stay tubes connecting the combustion chamber and boiler shell walls through which said tube connections extend.

5. In a boiler comprising an internal combustion chamber with a crown sheet roof and flues leading away from the combustion chamber, the improvement which consists in a radiant heat superheater comprising elements located in the combustion chamber immediately beneath the crown sheet, and means for passing the steam to be superheated first through one group and then a second group of said elements.

6. In a locomotive boiler comprising an

internal combustion chamber and a crown sheet forming the roof thereof and provided with fire tubes leading to the front end of the boiler from the combustion chamber, the improvement which consists in a radiant heat superheater composed of elements extending transversely to the length 25 of the boiler beneath the crown sheet, and tube connections to the ends of the elements extending to the exterior of the boiler, the tube connection at one end, at least, of each superheater element, being perpendicular to 30 the element.

Signed at New York city in the county of New York and State of New York this 14th day of May A. D. 1924.

WALTER FRANCIS KEENAN, JR.
